UNITED STATES PATENT OFFICE

105,611

DESIGN FOR A COAT

Nathan Prigozen, New York, N. Y.

Application June 14, 1937, Serial No. 69,824

Term of patent 3½ years

To all whom it may concern:

Be it known that I, Nathan Prigozen, a citizen of the United States of America, residing in Manhattan, county of New York, and State of New York, have invented a new, original, and ornamental Design for a Coat, of which the following is a specification, reference being had to the accompanying drawing, forming part thereof, wherein,

Figure 1 is a front view of a coat showing my new design.

Figure 2 is a rear view of the coat shown in Figure 1.

The stitchings extending around the front and

rear armhole portions of the coat represent quilting.

The rear collar portion of the coat has a one piece turned down extension, shaped and stitched as shown.

The characteristic feature of my design resides in the combination on the coat, as shown, of stitchings on the sleeves, giving an epaulette appearance, and in association with the collar of the specific configuration, as shown.

I claim:

The ornamental design for a coat, substantially as shown, and described.

NATHAN PRIGOZEN.
